(57) **CLAIM**

The ornamental design for a truck bed air mattress, as shown and described.

DESCRIPTION

FIG. 1 is a top, front, left side perspective view of a truck bed air mattress, embodying the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is bottom plan view thereof.

The broken lines in the figures are for the purpose of illustrating portions of the truck bed air mattress that form no part of the claimed design.

1 Claim, 4 Drawing Sheets
